United States Patent Office

Des. 224,090
Patented July 4, 1972

224,090

COMPARTMENTED COVER FOR A TRAY

Steve Cyr and Mark Whelan, Chippewa Falls, Wis.,
assignors to Standard Oil Company, Chicago, Ill.

Filed July 28, 1970, Ser. No. 24,185

Term of patent 14 years

Int. Cl. D9—07

U.S. Cl. D9—254

FIG. 1

F/6. 2

FIG. 3

FIG. 1 is a perspective view of a compartmented cover for a tray showing our new design;

FIG. 2 is a plan view thereof showing the interior;

FIG. 3 is a plan view thereof showing the exterior;

FIG. 4 is a front elevational view thereof;

FIG. 5 is a rear elevational view thereof; and

FIG. 6 is an end elevational view thereof, the end opposite being a mirror image.

We claim:

The ornamental design for a compartmented cover for a tray, as shown and described.
